Letter Patent

The Substitute referred to in these Letters Patent and in every part of the same containing a description in the words of the said Josiah Fay him self of his improvement in the art of cutting timber by rendering cylindric.

To all to whom these presents shall come. Be it known that I Josiah Fay of Miller in the County of Middleborough and State of New Hampshire have invented a new and useful improvement in the art of cutting timber by rendering cylindric and that the following is a full and exact description of the construction of my discovery or invention together with a frame necessary to contain the same. The machine consist of a frame forty two inches long and twenty inches wide to contain the lower cylinder directly over that is another frame of the same size to contain the upper cylinder and connected together at the ends by studs. The studs are made, and to the frame. The upper frame is confined to the said studs at one end by joint bolts and a half inches from the lower frame. The other end of the upper frame may be raised or lowered as the thickness of the timber to be cut may require and made fast by bolts that play in slots of said studs. The size of timber suitable for the frame is three by four inches and confined together by joint bolts. The cylinders are of cast iron seven inches in diameter at the face end and about one eighth of an inch left at the opposite end. They are three inches long and placed in the frame one directly over the other in nearly a horizontal position inclining a little towards each other at the whole end. so as to bring their surfaces at a parallel distance. They are supported in the frame by wrought iron staples having upon forty or centres. An inch cylinder are hoop plates passing through and set transversely with the surface of the cylinders and made fast by bolts and rivets at the face end and upon the edge of each cylinder are two plates fastened by iron keys to cut the timber thus of the timber which may be cut directly opposite or be saved by

Aug 29, 1831

moving forward the top of cylinder, as the nature and kind of the work may require. Upon each shaft is a wheel four inches in diameter for the band to run upon to put the cylinder in motion. They run on opposite directions by crooking the band on one wheel. Connected with the lower frame above described by two pieces of timber three and a half feet long, is a rail of the same length placed parallel with said frame. To this rail as well as to the side of the frame to which this is connected are cast iron angles which may be raised or lowered by a screw or keys so as to cut the shoulder to any required depth these angles are confined to the rails by bolts playing in holes. The carriage is a frame commanding in length with the ways, and about two feet wide. The end pieces of said carriage are one and a half by three inches, connected by two or more slats one inch thick and four inches wide. Upon the under side of the end pieces of said carriage are cast iron slides, and at the end, near the cylinder, the slides are ground so as to conform to the ways, and to govern the carriage in its movement. On the slats above mentioned is a movable slide consisting of two pieces, one inch thick and four inches wide confined together by screws with two or more grooves through it and corresponding with and for the slats to play in. This slide will move towards and from the cylinder, as the length of the timber to be tenoned requires, about the centre of the slides, fastened a spring with a perpendicular shoulder to keep the timber in its place lengthwise and to give the proper length of the shoulder of the tenons. On the end of the carriage next to the cylinder, under the slides above described are two movable blocks, confined by screws, to prevent the timber to be tenoned from moving sideways. At the forward side of the carriage on the end of the slide is a perpendicular pin or screw about four inches long upon which hangs a swivel about sixteen inches long with a movable hold fast upon it to confine the timber against the blocks above described. Upon this carriage the timber to be tenoned being placed secured in its place as above mentioned and the cylinder being put in motion to rotate a other frame. The end of the timber to be tenoned by a little manual exertion, is thrown forward passing at any given distance round between the cylinder

The spines are the shoulders and on the plane sides are the surfaces of the
timers, leaving them perfectly smooth. The principle of this invention or
discovery is to cut timber by sawing, exploring. And your petitioner has
contemplated it as suitable to be applied to the cutting of masts.
Your petitioner claims the ~~importance~~ of cutting timber by sawing, exploring
as an invention or discovery of his own.
